UNITED STATES PATENT OFFICE

2,401,107

ADJUSTABLE SPLINT

George Richmond, Brooklyn, N. Y.

Application June 15, 1943, Serial No. 490,864

5 Claims. (CL. 128—85)

The present invention relates to appliances for immobilizing splinting, and for supporting fractured limbs, and has for its principal object the provision of a device of the character described, designed primarily for use in emergencies, though the appliance is capable of effective surgical use generally.

Essentially, the device, because of its simplicity of operation, can be used efficiently, even during blackouts, gas attacks, air-raids, or other hazardous conditions.

Among the features of the present invention is the provision of a strong but light extensible splint, which can be applied to arm or leg and is adapted to afford support to the limb as well as being adapted to enable traction and countertraction. In addition, a single splint can be used in an emergency for immobilization of both lower limbs; one or more splints can be utilized for fractured ribs, injuries to the chest, injuries to the spine or injuries to the pelvis with a little simple adjustment.

Furthermore, X-rays can penetrate the wooden splint, thus enabling X-ray photographs to be taken with the splint in place without the interference of metal objects. The canvas cover, in addition, allows air to enter an underlying wound.

Another feature of the present invention is the provision of a wrap-around material provided with spaced pockets into which splints of the special type herein disclosed, or simply boards of suitable width, may be inserted. The area between said padded pockets is made as wide as need be, to accommodate the affected limb, to defend the skin from the pressure of the wooden splint producing the aggression of "splint sore." Said wrap-around is preferably provided with strap means to prevent unrolling of the wrapping, and with ties or tapes for putting traction on the limb, or other purpose. Other features of the present invention will appear as the description proceeds.

The accompanying drawings illustrate the various features of invention. In the drawings:

Fig. 1 is a plan view of a wrap-around with the splints of my invention disposed in the pockets thereof.

Fig. 2 is a vertical elevation showing part of the wrap-around with pocket containing the splint of my invention, showing the protrusion of the hand-grasp element from the top opening in said pocket.

Fig. 3 is a lefthand end view of Fig. 1, but show-

ing both splint pockets with enclosed splints, on edge.

Figs. 4 to 7 are exploded views of the splint.

Fig. 8 is a top edge view of a removable splint.

Fig. 9 is a sectional view on line 9—9 of Fig. 13.

Fig. 10 is a sectional view on line 10—10 of Fig. 13.

Fig. 11 is a sectional view on line 11—11 of Fig. 13.

Fig. 12 is a sectional view on line 12—12 of Fig. 13.

Fig. 13 is a plan view of the splint in partially extended condition, as seen in Fig. 8, and showing the interior construction and assembly.

Fig. 14 is a plan view of a modification of the form of splint illustrated in the previous figures.

Fig. 15 is a section on line 15—15 of Fig. 14.

Fig. 16 is a similar section showing a somewhat different means for holding the members of the splint together.

Fig. 17 is a partial perspective view showing another modified form similar to Fig. 14.

Fig. 18 is a fragmentary perspective view showing one end of the splinting device applied to a limb with traction means being utilized.

Fig. 19 is a cross-section of Fig. 18 through limb and splints.

Fig. 20 illustrates an adaptation of my appliance to provide a stretcher or cot, as the case may be.

Referring now more particularly to Figs. 4, 5, 6, and 7, it will be observed that the splint consists of two members slidably relatively to each other to extend or shorten the splint. One member consists of a panel 2 in outline substantially identical with that of cover panel 3. To said panel 2 is attached, by screws, nails or glue, certain reinforcing and guiding elements, which are respectively the strip 4, the hand grasp piece 5, the piece 7, the strip 8, to which is secured near one end the arched leaf spring 9, and the guide rail 10. The extending portion 11 of panel 2 is provided with ratchet teeth 12, each tooth being defined by a vertical or straight face and an inclined face. Teeth may be round, square, oval, saw-tooth, gear-like, spike, top square or half-round, either straight or inclined.

The complementary member 13 consists of a panel 14 substantially identical in form and size with covering or outer panel 15. To said panel 14 is attached, by screws, nails or glue, certain reinforcing guiding elements, which are respectively the strip 16, the piece 17, the strip 18, and the guide rail 19 which terminates in an upstanding portion 19a which functions as a stop, as

55

will later be made clear. To the strip 16 is attached near one end thereof, an arched spring leaf 20. The extending portion 21 of panel 14 is also provided with ratchet teeth 22 similar but opposite to the teeth of panel 2. It will be observed that teeth 12 and 22 are complementary, so that when the said members are assembled, as shown in dotted lines in Fig. 13, the "peaks" of the one will enter the "depressions" of the other, with vertical edges abutting vertical edges, and are purposely made in the form shown so that when the teeth coincide, it will be impossible to move panel 2 longitudinally relative to panel 14.

Panel 2 is substantially identical with panel 3, except that the ratchet teeth 12a in the latter "run" in the opposite direction to that of the teeth in panel 2. This observation is also true with respect to the difference in direction of "run" of the teeth 22—22a between panels 14 and 15. Now looking at panels 3 and 15, it will be seen that their teeth are complementary and when meshed, will prevent the movement of the panels toward each other to shorten the ostensible length. Now, when panels 2 and 4, with their respective appendages, are assembled, as shown in Fig. 13, and the covering panels 3 and 15 attached respectively to units 2 and 14, it will be impossible to move members 1 and 13 relative to each other, except by unmeshing or separating the teeth, which is accomplished by grasping the hand grasp 5 in one hand and the member 13 in the other and pulling them apart, as indicated by the arrows in Fig. 13. It is then possible to move members 1 and 13 relative to each other, to shorten or lengthen the splint, and when the desired length is achieved, the parts are released, and the teeth will be brought and kept in mesh again through the action of the arched leaf springs 9 and 20 respectively, normally acting to exert pressure against guide rails 10 and 19, and thus keep the members to which they are respectively connected, securely locked against inadvertent change in length of the splint.

The upper edge of member 1 is provided with a series of reentrant notches or slots 23, 23, adapted to receive dowel rods, tape or the like, as the exigencies and procedure may require. The outer end of member 1 is also provided with a longitudinal open slot or notch 24, preferably of substantially keyhole outline. The outer end of member 13 is provided with what is known as a crotch curve 25 so that it may be comfortably accommodated in the armpits or crotch of the legs.

Referring now more particularly to the wrap-around, as illustrated in Figs. 1 to 3 inclusive, the same comprises a sheet of canvas 30 to which is attached by stitching or otherwise, pockets or sleeves 31, 31, spaced apart a predetermined distance, said pockets or sleeves being preferably open at both ends, and having each a longitudinal opening 32 therein where the wrap-around is to be used in conjunction with my splint, as above described. Attached to said pockets are straps 33, 33, bearing each a complementary unit 34a of snap fastener means, arranged to engage its complementary fastener 34b, 34b, located on the other side of the opening 32, as more clearly shown in Fig. 3. Removable pads 36 may also be provided for attachment in any suitable manner to the faces of the pockets or sleeves 31. Tapes 37, 37, are provided to tie up the wrap-around, while relatively long tapes 38, 38, are provided to effect traction, and so on.

Figs. 1, 2, and 3 illustrate the manner in which

the splints are disposed in the pockets or sleeves. Fig. 2 shows the operative position of the appliance for receiving the affected limb.

It is to be particularly noticed that the splints disposed within the pockets 31, 31, can be lengthened or shortened without removing the same from said pockets. All that is required is that the hand grasp 5 be grasped in one hand while the bottom of the pocket containing and including the splint is grasped in the other, and a pull exerted in opposite directions perpendicular to the plane of the splint. This will unmash the complementary teeth and enable the members 1 and 13 to be moved longitudinally relative to each other to effect the desired change in length.

If desired, additional snap fastener means may be provided for preventing the flaps of the wrap-around from unrolling when operatively functioning. Such snap fastener means are members 39, 39, which may be arranged to engage either of the complementary members 39a, 39a, in line therewith.

Fig. 20 shows an adaptation of my appliance as a cot. This appliance comprises a sheet of canvas or similarly strong fabric or material 40 having a pair of spaced-apart pockets 41, 41, in which are disposed preferably boards 42, 42 of substantial height.

Referring now particularly to Figs. 14, 15, 16, and 17, the splint illustrated therein comprises two solid members 50 and 51, the former having a longitudinal groove 52 in the upper edge of the extension 50a, while the corresponding edge of extension 51a is provided with a longitudinal spline 53 adapted to move in said groove 52. In order to maintain the predetermined adjusted relation of the parts, spring fingers 54, 54, may be provided, adapted to enter holes 55, 55, in extension 51a, said fingers being attached at their lower ends to extension 50a (Figs. 14 and 15), as indicated at 56. In lieu of said spring fingers detachable U-shaped spring clips 57 (Fig. 16) may be employed, in which event extension 50a will be provided with a series of holes 58 in alignment with holes 55 in extension 51a. The ends of said clips are preferably provided with outwardly bent portions 57a, to retain the clips in place under all normal conditions, it being possible and intended to enable forceful removal of said clips when desired, as by inserting a blade between the clip and the board. The same expedient is applicable to the withdrawal of the spring finger from engagement in hole 55.

In lieu of the teeth on the panels—the teeth can be constructed on the guide rails 10a and 19a, as shown in Fig. 17, with clips 17b being used to secure the parts together.

What I claim as new and desire to secure by Letters Patent is:

1. A splint comprising a pair of members in edge to edge interfitting relation, complementary cooperating teeth on the confronting edges of each member, said members being in longitudinal relative adjustable engagement, and yielding means for normally maintaining said members with their teeth interengaged to maintain them locked against relative longitudinal movement, said members being manually movable apart in the plane of their sides to disengage the teeth to permit relative longitudinal movement.

2. An extensible splint comprising a pair of flat members, each provided with spaced apart panels and extensions therefrom having teeth along their inner longitudinal edges, guide rails secured to the respective members, each rail pro-

jecting into the space between the panels of its companion member, and spring means disposed in said members and bearing against said rails normally to retain the teeth of the respective members in mesh, said teeth being brought out of mesh by exerting a pulling-apart force on the said members perpendicular to their longitudinal axis.

3. An extensible splint comprising a pair of flat members, each provided with spaced apart panels and extensions therefrom having teeth along their inner longitudinal edges, guide rails secured to the respective members, each rail projecting into the space between the panels of its companion member, one of said rails having a limit stop element at one end arranged to engage the corresponding end of the other rail, and

spring means disposed in said members and bearing against said rails normally to retain teeth of the respective members in mesh, said teeth being brought out of mesh by exerting a pulling-apart force on the said members perpendicular to their longitudinal axis.

4. A splint in accordance with claim 2, wherein the teeth are so designed and arranged that relative movement, by either longitudinal pull or push of the members relatively to each other, is precluded.

5. A splint in accordance with claim 3, wherein the teeth are so designed and arranged that relative movement, by either longitudinal pull or push of the members relatively to each other, is precluded.

GEORGE RICHMOND.
